(57) **CLAIM**

The ornamental design for a rolling multi-function tool stool as shown and described.

DESCRIPTION

1. Rolling multi-function tool stool
- 1.1: Perspective
- 1.2: Perspective
- 1.3: Front
- 1.4: Back
- 1.5: Left
- 1.6: Right
- 1.7: Top
- 1.8: Bottom

1 Claim, 8 Drawing Sheets
